**APPARATUS FOR PRINTING AN ORIGINAL
ON TO A COPYING PAPER**Werner Salger, Hamburg, Germany, assignor to
Lumoprint Zindler KG, Hamburg, Germany

Filed Sept. 1, 1960, Ser. No. 33,539

Claims priority, application Germany Sept. 23, 1959
3 Claims. (Cl. 95—77.5)

The present invention concerns an apparatus, for printing an original on to a copying paper, including an exposure light source, a feeding device for the original and the copying paper and a printing plate disposed between the feeding device and the light source.

Various methods are used for producing copies with such printing devices. In the diffusion method, for example, a negative emulsion support together with the original is passed through the exposure device. When using a heat developing method a copying paper is passed through on which later the image is developed.

Known printing devices have a transparent exposure plate which may be flat or curved. Pressure application bands or a roller are known as feeding devices.

Transparent printing plates are comparatively expensive not only due to the material used which must have a uniform permeability to light but also due to the processing because these plates require special fixing means or frames.

These known plates become soiled in course of operation, for example, in that dust collects on the surface of the plates. These plates in known devices are not readily accessible thus making cleaning difficult.

There is a further disadvantage of plates becoming soiled on the underside because either the copying papers or feeding devices rub dust over the underside. In this case the use of certain materials could also result in damage by scratching or the like.

The present invention removes the disadvantages of known printing devices by the feature that the printing plate is provided with apertures which are so arranged in relation to the direction of feed of the original and of the copying paper that every point of the paper is subjected for an equal period and to an equal extent to the influence of the light source.

Such apertures, when the printing plate is made from transparent material, involve substantial advantages, because a self-cleaning action takes place on the underside.

It is impossible for any dust to collect in the region of the apertures on the surface. By this means perfectly clear regions are always available for effecting the exposure.

One particular advantage is due to the fact that it is now possible for the printing plate to be produced in opaque materials, preferably metal, for example in plastics material. Beside the substantial reduction of manufacturing costs there is also obtained the additional advantage of easier processing in that no special holding means have to be fitted on the plate itself. It is possible, for example, for a sheet metal plate to be extended beyond the exposure device and to use it simultaneously as a guiding element in the adjacent parts of the device.

When a cylindrical feeding mechanism is used the plate may be readily and accurately adapted to the curvature of the roller.

In accordance with one preferred feature the apertures

2

are slot-shaped and arranged obliquely to the direction of feed of the paper. The slots are conveniently wider than the webs remaining therebetween.

In accordance with another preferred feature with the width of slot in relation to the length of slot and inclination of the slots relative to the direction of feed is such that in all cases the sum of all imaginary parallels to the direction of feed of the sections disposed in the slots is equally long.

With the arrangement of the apertures, more especially the slot-shaped apertures, in the printing plate there is a possibly that the corners or edges of the paper passing through are caused to be curled up within the apertures. This is obviated in a particularly preferred embodiment by means of edges extending at least on one side of the aperture from the centre line of the conveying track for the original and the copying paper outwardly in the direction of feed. These edges may be rectilinear and/or curved.

The apertures are preferably so arranged and/or staggered relative to one another that the parallels, extending through these apertures and spaced at least 3 mm. from the centre line relative to the direction of feed, intersect at least one of these aperture edges extending obliquely in an outward direction on the side of the apertures facing the centre line. In one particular embodiment all parallels fulfill these conditions relative to the direction of feed.

In an embodiment having slot-shaped apertures the slots extend in the direction of feed obliquely in an outward direction from the centre line of the conveying path. In this case a substantially triangular aperture is conveniently provided which is flared in the direction of feed, this aperture, for example, having however a flattened tip. One preferred form of construction includes webs arranged between the apertures which extend obliquely outwards from the centre line in the direction of feed, which apertures are provided with front and rear edges disposed at right angles to the direction of feed. In this construction width and length of the slot is such relative to its inclination that each parallel to the direction of feed intersects a web or in the centre line a web portion between the apertures. In this case the webs are preferably rectilinear with parallel sides.

If only one source of radiation is used above the printing plate and, for example, a printing plate is provided which is so curved that the distance between the light source and the printing plate is considerably increased towards the ends of the printing device, then in a further preferred form of construction of the invention the ends of the slots are enlarged. The enlargement is such that a longer period of exposure on the parts of the paper concerned is obtained when these parts are situated at a sufficient spacing from the light source. From the same aspect in a special form of construction, when using slots disposed obliquely relative to the direction of feed, at least one end of the slots are bent off in a direction parallel relative to the direction of feed.

The invention is not limited to a slot-shaped design of the apertures. In one particular embodiment, for example, round or substantially rectangular apertures are arranged in several rows offset relative to one another. In this case it is also possible to fulfill the condition that all sections of the paper pass beneath the apertures for the same time period.

65

The invention will be described further, by way of example, with reference to the accompanying drawings, in which:

FIG. 1 is a diagrammatic sectional side elevation of a printing device on the line I—I of FIG. 2;

FIG. 2 is a sectional plan view of the device of FIG. 1 on the line II—II of FIG. 1;

FIG. 3 is a fragmentary elevation of the printing plate viewed from above on a larger scale;

FIG. 4 is an alternative embodiment of the printing device shown diagrammatically by way of a partial side elevation; and

FIG. 5 is a plan view of a detail of an alternative embodiment of the printing plate.

FIG. 1 only shows the essential parts of a printing device. A printing plate 2 is arranged below the light source 1, for example, a fluorescent tube, a feeding device constructed as a roller 3 abuts against this plate. The roller is driven by a motor in the direction indicated by the arrow 4.

The aforementioned parts are arranged in a housing 22. The roller 3 is rotatably mounted by means of its journal ends 23 and 23' on the one hand in an end face 24 of the housing and on the other hand in an intermediate wall 25 of the housing. The journal end 23' is coupled with the driven shaft of a motor driving unit 26 which is arranged in a separate chamber 25' on one side of the housing. This chamber moreover also includes a power unit 26' from which on the one hand lead-in wires 27 are led to the motor driving unit 26 and on the other hand lead-in wires 28 to the light source 1. From the power unit an actuating member 29, for example, for a switch is led to the outside through the housing wall to enable the device to be switched on. The power unit moreover also includes an exposure timer which is conveniently adapted to be set from the outside. A reflector 30 is provided over the exposure light source 1.

The printing plate 2 by means of a section 5 arcuate in accordance with the curvature of the roller abuts against the roller 3. A resilient application pressure is obtained in the illustrated embodiment the end of the plate 2 being extended in the direction of feed and provided with pivots 6, 31 in which pivot pins mounted, for example, on the device walls, are guided. The other end 8 of the printing plate 2 extended to act as guide surface for the introduction slot 7 is drawn downwardly by means of the spring 9, i.e. drawn against the roller 3. The end of the spring 9 remote from the end 8 is anchored in an abutment 10 which is fixed on the housing, not shown in the drawings.

Below the end 8 of the printing plate which act as guide element there is an introduction slot 7 defined downwardly by means of a fixedly arranged guide element 11.

An outlet slot 32 is arranged in the side wall of the housing situated opposite to the introduction slot. On one side of this outlet slot there is a guide element 33 which extends to the facing edge of the plate 2. On the other side of the slot 32, i.e. on the lower side, a guide element 34 is fixed on the housing which is extended into the interior of the housing close to the roller 3 and adapted to extend with clearance beneath the plate 2 to the extent the latter projects beyond the roller 3.

As evident from FIG. 2 the printing plate 2 is provided with slots 12 in the section abutting against the roller 3, the slots extending uniformly obliquely relative to the direction of feed of the paper and/or at right angles relative to the axle of the roller 3. The plate 2 in the embodiment shown consists of sheet metal.

The arrangement of the slots 12 is shown on a larger scale in FIG. 3. It should be noted that the webs 13 between two adjacent slots 12 are far wider apart than the slots. FIG. 3 moreover shows lines 14 parallel to the direction of feed. The section 15, 16 and/or 17, 18, 19 or 20, 21 of a line 14 in combination are equally as long as the corresponding sections of another line. This ensures

a uniform exposure of all sections of the paper passing through.

The condition for a uniform illumination of the plate 2 is truly fulfilled by the present invention. This condition also obtains in the arrangement shown in FIG. 1, in which the ends of the slots 12 due to the curvature of the plate 2 have a greater distance from the light source 1, than the centre sections of the slots. It is quite within the scope of the invention to create a balance to widen the ends thereof, for example, or even to change the course of the slots at their ends. The ends of the slots can be bent off in a direction parallel to the lines 14, the arrangement then being such that the web portions between the slot ends situated parallel to the direction of feed cover sectional areas of the paper which travel along beneath the centre region of the slots.

The arrangement of the slots shown presents a preferred embodiment. The length and oblique position of the slots may be varied provided that a uniform and sufficient exposure is obtained. It is also possible to use apertures of different shape which with regard to the path taken by the paper through the printing device ensure a uniform exposure of all sections of the paper.

FIG. 4 is a side elevation of a detail of an exposure device the construction of which is readily comprehensible from illustration in FIG. 1. In accordance with FIG. 4 housing walls corresponding to the housing walls 24, 25 in FIG. 2, a detail of one housing wall of which is being shown and denoted by the numeral 35, have two light sources 36, 37 mounted thereon which are arranged above the feed device which is preferably in the form of a roller 38. The roller is driven in the direction of the arrow 39. The roller, for example, is made of rubber and preferably provided with a jacket of plastics material and/or a plastics material permeated by a fabric.

The original and the copying paper are fed to the roller 38 in the direction of the arrow 39. In this case the papers are received by a guide track which on the one side is defined by the guide surface 40, which terminates at the roller and on the other side is defined by the guide surface 41. The guide surface 41 merges into the exposure plate 42 which at least over a sector of the arc concentrically embraces the roller 38 and then merges into a section serving as guide element 43 for forwarding the papers. The section 43 can also have a further guide element 44 associated therewith which at its end facing the roller 38 may be provided with a special device adapted to receive the papers from the roller jacket.

In the region of exposure, of the paper which is passing through the printing plate 42 is provided with apertures, a preferred arrangement of which is shown in FIG. 5.

FIG. 5 is a plan view of the central section of the printing plate 42. The centre line of the conveying track through the printing device is denoted by the numeral 45. Moreover the direction of feed of the paper is indicated on the plate 48 by means of the arrow 46. It is evident that slots 47, 48, 49 etc., and/or 50, 51, 52 etc. are provided on either side symmetrically relative to the centre line in such a manner that the ends of the slots disposed in the direction of feed of the papers have a greater distance from the centre line 45 than the opposite ends at which the papers being fed in accordance with the arrow 46, reach the slots 47 and 52.

In the preferred embodiment of the slots having rectilinear sides, webs 53, 54, 55 etc., and/or 56, 57, 58 etc., are formed between the slots corresponding to the direction of feed and having a greater spacing from the centre line. The webs situated on different sides of the centreline 45 hence diverge in the direction of feed. The webs 59, 60 disposed near to the centre line 45 are thus disposed substantially in the form of a V to one another and define therebetween a substantially triangular aperture 61, the point of which lying opposite to the direction of feed being truncated. To facilitate manufacture, uniform lighting and confining the printing device to

the smallest possible space the apertures 47 to 52 and 61 are provided at their sides situated at the front and rear in the direction of feed with edges disposed at right angles to the direction of feed.

The width of slot is such that the webs formed between the slots at least partly overlap one another so that apart from a central region corresponding to the distance 62, all portions of the paper passing through the device and which reach the region of an aperture situated at an edge extending at right angles to the direction of feed, pass beneath at least one of the web edges situated outward of the centre line, which edge as stated above extends in the direction of feed of the paper outward of the centre line. To explain this feature reference is made to the parallel 63 shown in the drawing relative to the centre line. This parallel is laid by means of the outward end of the lower edge 64 of the aperture 65 and reaches the adjacent web 66.

By this means it is ensured that corners which may possibly curl upwards in the aperture are smoothed by oblique outwardly directed leading edge of the webs and urged against the roller 3 or 38 without there being a risk of such corners being damaged, for example, by striking against edges of apertures.

It is to be pointed out that for this purpose, for example, the direction of feed of the front edges of the apertures can also be caused to extend obliquely forwards and outwards. In this case it will also be necessary to effect corresponding alterations to the edges of the aperture disposed to the rear in the direction of feed to produce a uniform exposure.

The sections on the parallels 63, 67, 68 which are situated in the region of a web are designated *a*. It is evident that these distances *a* are equal for all parallels to the centre line. Even in the region of the centre line 45 a distance *a* between the slots 47, 50 in the region of the slot arrangement is covered by a web element which corresponds to the cut off point of the substantially triangular aperture 61.

The arrangement is such that each parallel 62, 63, 67, 40 68 intersects a web only once. The invention also concerns other constructions wherein several webs are intersected by the parallels, the sum of the sections disposed beneath different webs of individual parallels being equal.

It is evident that the distances designated *b* on the 45 parallels extending in the region of apertures are each equal.

Additionally it is pointed out that the present invention is not limited to the use of a curved printing plate; it is possible, for example, by simultaneously arranging 50 other feeding devices, to use a flat printing plate 2.

Sheet metal has been mentioned above as a preferred material because it is a good heat conductor, thus obtaining at the same time an improved dissipation of heat from the printing device. The invention concerns all 55 transparent and, with particular advantage, opaque materials.

It is pointed out that the invention is not limited to the described details and embodiments. It is obvious to experts that modifications and arrangements of details are possible and these modifications and arrangements of detail reside in the nature and in the scope of this invention to the extent at which they are characterised in the appended claims.

What is claimed is:

1. An apparatus for printing an original on to copying paper comprising a housing, a printing device arranged in the housing, inlet means in a housing wall for feeding the original to the printing device, outlet means in a housing wall for discharging the original and the copying paper from the printing device, the latter being provided with an exposure light source which is arranged in the housing, a feeding mechanism comprising a roller arranged at a clearance in front of the light source between the inlet and outlet means and adapted to convey

the original and the copying paper from the inlet means to the outlet means, a printing plate arranged between the light source and the feeding mechanism in the housing having a curved section complementarily conforming to and adjacent to said roller and in which the feeding mechanism is guided in order to lead the original and the copying paper past the printing plate, one end of said plate being pivotally mounted to said housing and means biasing the other end of the plate to urge the plate against the roller, said printing plate being provided with apertures formed in said curved section which, in relation to the direction of feed of the original and the printing paper are so arranged that each point of the papers is subjected to the influence of the light source over an equally long period and/or to an equal extent, a driving means driving the feeding mechanism roller and connecting means to connect at least one light source.

2. An apparatus for copying an original on to copying paper comprising, in combination, a housing, an original and copy paper transport means within said housing for conveying said papers therethrough, inlet and outlet openings defined in said housing aligned with said transport means for receiving and discharging said original and copying papers, an exposure light source within said housing, said transport means including a light impervious printing plate interposed between said light source and the papers passing through said transport means, apertures defined in said plate permitting light to pass therethrough, said apertures including first and second sets of evenly spaced, parallel slots obliquely arranged to the direction of movement of said papers and having front portions, the angle of the slots of a set and the spacing between the slots being such that all portions of papers transported past said slots will be equally exposed to said light, said first and second sets being angularly related in opposite directions with respect to the central regions of the path of movement of said papers and transversely disposed thereto at a common location in said path, a composite aperture defined in said plate centrally intermediate said first and second aperture sets for exposing the central region of the papers transported past said slot sets, said composite aperture including opposed sides, each of said sides being adjacent and parallel to the slots of one of said sets, the maximum dimension of said composite aperture in the direction parallel to the paper's path of movement being substantially equal to the exposure dimension defined by said slots in the direction parallel to the paper's path of movement the front portions of the slots of each set first exposing said papers being nearer the central region of the paper's path of movement than the slot portions located behind said front portions with respect to the paper's direction of movement.

3. An apparatus for copying an original onto copying paper comprising, in combination, a housing, an original and copy paper transport means within said housing for conveying said papers therethrough, inlet and outlet openings defined in said housing aligned with said transport means for receiving and discharging said original and copying papers, an exposure light source within said housing, said transport means including a light impervious printing plate interposed between said light source and the papers passing through said transport means, apertures defined in said plate permitting light to pass therethrough, 65 said apertures including first and second sets of evenly spaced, parallel slots obliquely arranged to the direction of movement of said papers, the angle of the slots of a set and the spacing between the slots being such that all portions of papers transported past said slots will be equally exposed to said light, said first and second sets being angularly related in opposite directions with respect to the central regions of the path of movement of said papers and transversely disposed thereto at a common location in said path, a composite aperture defined in said

plate intermediate said first and second aperture sets for exposing the central region of the papers transported past said slot sets, the front portions of the slots of each set first exposing said papers being nearer the central region of the paper's path of movement than the slot portions located behind said front portions with respect to the paper's direction of movement, said transport means including a cylindrical roller rotatably and drivingly mounted within said housing, said printing plate having a cylindrical portion complementarily shaped to and en-

gaging said roller, said slots being defined in said plate cylindrical portion.
